COVERING FOR A SKATE SHOE

Jack Adams, 723 Morris Park Ave., New York, N.Y.

Filed Apr. 11, 1960, Ser. No. 60,139

Term of patent 14 years

(Cl. D7—7)

FIG. 1 is a front perspective view of a covering for a skate shoe as it appears when in wearing position;

FIG. 2 is a bottom plan view thereof;

FIG. 3 is a side elevational view thereof;

FIG. 4 is a front elevational view thereof;

FIG. 5 is a top plan view thereof; and

FIG. 6 is a side elevational view of the shoe protector as it appears when in flat condition.

I claim:

The ornamental design for a covering for a skate shoe, as shown.
